ACTUATING MECHANISM FOR RECIPROCATING CARRIAGES

Royal E. Crossley, Fayetteville, N. Y., assignor to
Crouse-Hinds Company, Syracuse, N. Y., a corporation of New York

Application August 2, 1950, Serial No. 177,221

5 Claims. (Cl. 74—59)

1

This invention relates to actuating mechanism for reciprocating carriages. While the invention is applicable to the reciprocation of carriages in machines and apparatus of various types, it is here shown in connection with shifting the lamp or light source in a lighting unit. In lighting units of certain construction, the direction of the output beam may be varied by moving the light source within the unit. Such units are used, for example, in airport lighting systems, and it is desirable to shift the light sources of a number of lighting units simultaneously and to the same extent. At the present time, the mechanism for so moving the light sources consists of a motor driven screw, the motor being of the reversible type and functioning to move the lamp receptacle back and forth along the axis of the screw.

In order to assure uniform positioning of the various light sources, or lamps, in moving the same from any given position, the motor is energized and operated until the lamp receptacle, or the carriage on which it is mounted, is threaded along the screw to the end thereof, at which time the motor is stalled, and this means that the motors in all the units are stalled until the light source in the last unit has reached the end of its travel.

This invention has as an object an actuating mechanism of the type referred to which embodies a structure which functions to relieve the carriage propelling screw from any restraint when the carriage has moved to either end of its travel by the screw, leaving the motor free to rotate under no load.

The invention consists in the novel features and in the combinations and constructions hereinafter set forth and claimed.

In describing this invention, reference is had to the accompanying drawings in which like characters designate corresponding parts in all the views.

Figure 1 is a plan view of a device embodying my invention.

Figure 2 is a view taken on line 2—2, Figure 1.

Figure 3 is a view taken on line 3—3, Figure 1.

Figure 4 is a view taken on line 4—4, Figure 2.

Figure 5 is a view corresponding to the lower portion of Figure 2, showing the latch stop in nut releasing position.

Figure 6 is a view taken on line 6—6, Figure 3.

The frame 10 is a U-shaped plate member having extensions 11 on the leg portions thereof provided with apertures 12, and the opposite end of the frame has a similar aperture 13. These

2

apertures receive screws by which the device is mounted in a lighting unit, such as a searchlight. The frame 10 is formed with upwardly extending projections 14, there being a pair of these projections at each end of the frame and they are apertured to receive rods or guideways 15. Like ends of the rods are threaded into the projections 14 at the open end of the frame and are secured in place by jam nuts 16 which also serve to mount a disk 17 to which the legs of a driving motor 18 are secured by means of screws 19.

The lamp receptacle 20 is mounted on a carriage 21 formed on one side with a pair of upwardly extending bifurcated projections 22, and with a similar projection 23 on the opposite side. Rollers 25 are rotatably mounted in the projections 22, 23, and are positioned on the guide rods 15, whereby the carriage 21 is movable lengthwise of the frame plate 10. The lamp receptacle 20 is mounted on an angle bracket 28 by screws 29. The other leg of the bracket is formed with a square recess to receive a post 30 rectangular in cross section, and the bracket is adjustably clamped to the post by a cap 31, as by screws 32. The lower end of the post 30 is positioned in an aperture formed in the carriage plate 21 and is fixed thereto as by set screw 33.

The output shaft 36 of the motor 18 has secured thereto a screw 38 extending lengthwise of the frame between the side legs thereof. A nut 40 is mounted on the screw 38 in threaded engagement therewith and is operatively connected to the carriage by an H-shaped member having a pair 41 of its leg portions straddling the receptacle mounting post 30 and being secured to the carriage 21, as by screws 42. The leg portions 43 of this member are formed with depending projections 46 positioned between the side legs of the frame 10 and on opposite sides of the nut 40. The legs 41 of the H member are provided with elongated apertures 47 to permit adjustment of the member lengthwise of the carriage. The nut 40 is formed with a circumferential groove 49 and the depending portions 46 carry pins 50 extending into the groove 49. Accordingly, when the nut 40 is moved axially of the screw 38, the carriage is similarly moved on the guide rods 15.

The frame 10 is formed with a bridge portion 52 extending transversely below the screw 38 and is formed with a threaded aperture extending parallel to the screw into which screws 53 are threaded and on which are journaled latch members 54, 55. The bridge member 52 is formed with a ridge 56 extending below the screw 38.

and parallel therewith. The nut 40 is provided with a pin 57 arranged to engage the ridge 56 upon rotation of the nut when the nut, or the pin 57, is positioned over the ridge. In other words, the ridge 56 is cooperable with the pin 57 to prevent rotation of the nut on the screw.

The latch members 54, 55, are also formed with projections 59 normally positioned in registration with the ridge 56 and being maintained in that position by a projection 60 extending parallel to the screws 53 toward the bridge 52 and engaging the under side thereof. The projections 60 are moved into engagement with the bridge by the longer and heavier arm portion 61 of the members 54, 55. The members 54 and 55 are mounted in reverse relation—that is, the longer portions 61 on the member 54 extending in the opposite direction to the portion 61 of the latch member 55, see Figure 2.

If power is supplied to the motor 18 to rotate the screw in a clockwise direction Figure 2, the nut will be threaded along the screw 38 to the left Figure 3, the pin 57 riding along the ridge 56 on bridge portion 52. When the pin 57 passes off from the ridge 56, it will engage the ridge 59 on the latch member 55. When the pin engages the ridge 59, the latch member 55 will be moved about its screw 53 in a clockwise direction, whereby the ridge 59 will be moved out of engagement with the pin 57, permitting the nut to rotate with screw 38, whereupon movement of the carriage 21 to the right, Figure 3, ceases. The motor can continue to rotate the screw 38 in the counter-clockwise direction Figure 2, and the nut will continue to rotate as each time the pin 57 engages ridge 59 on the latch member 55, the ridge 59 thereof will move about the axis of screw 53 out of engagement with the pin. However, if the motor is reversed and the screw operated in a clockwise direction, Figure 2, the first time the pin 57 engages the ridge 59 of the latch member 55, the latch member will stop movement of the pin and rotation of the nut, and the nut will thereupon be threaded along the screw toward the motor 18, with the pin passing from the ridge 59 onto the ridge 56 and the nut and carriage will continue to travel towards the motor until the power is turned off from the motor, or until the pin 57 engages the ridge 59 of the latch member 54, whereupon that latch member will be moved in a counter-clockwise direction about its mounting screw 53 to release the pin, this taking place each revolution of the nut as previously explained.

Accordingly, regardless of the length of time current is supplied to the motor 18, the carriage 21 carrying the lamp receptacle will be moved only to some predetermined point in respect to the reflectors of the units. On a long runway of several thousand feet employing a multiplicity of lighting units, the lamp receptacles will not all reach this predetermined position simultaneously, this due to voltage drop in the line supplying the motors, the variation in frictional resistance of the units, etc. However, the operator can leave the power supply on the motors until he is certain that the lamp receptacles of all the units have reached the selected position. The fact that some of the units will reach this position ahead of others is of no moment because the nuts 40 on those units simply idle, or rotate with the screw, without placing any undue burden upon the associated motor 18.

After the lamp receptacles of all the units have reached this predetermined position, the operator can then reverse the line current to the mo-

tors and the lamp receptacles will all move forwardly in unison to whatever position the operator desires.

What I claim is:

5. Actuating mechanism for a reciprocating carriage comprising a frame, a carriage actuating screw journalled in the frame and extending parallel to the movement of the carriage, a nut threaded on said screw, said carriage having 10 means cooperable with the nut to permit rotation thereof and to restrain axial movement of the nut relative to the carriage, a fixed stop member arranged in juxtaposition to the screw and extending in parallel spaced relation thereto and 15 being cooperable to restrain rotation of the nut during movement thereof axially along the screw, latch members mounted at the ends of said stop and cooperable to permit rotation of the nut in one direction only, and a reversible 20 motor operatively connected to said screw to effect rotation of the same to cause reciprocation of the nut and carriage lengthwise of the stop member.

25. Actuating mechanism for a reciprocating carriage comprising a frame, a carriage actuating screw journalled in the frame and extending parallel to the movement of the carriage, a reversible motor operatively connected to one end of the screw, a nut threaded on the screw, 30 said carriage and nut having means cooperable to permit rotation of the nut and to restrain axial movement of the nut relative to the carriage, an elongated stop member carried by the frame and extending in parallel spaced relation to the screw, 35 said nut being provided with a projection movable into engagement with said stop member and being slidable therealong to restrain rotation of the nut during axial movement thereof along the screw, a latch member mounted at each end of 40 said stop member, each of said latches being formed with a portion normally positioned to constitute a continuation of said stop member, the latch at one end of said stop member being cooperable with said projection to permit rotation of said nut in one direction only and to restrain rotation of the nut in the opposite direction, the latch member at the opposite end of said stop being operable in reverse order.

45. Actuating mechanism for a reciprocating carriage comprising a frame, a carriage actuating screw journalled in the frame in parallel relation to the movement of the carriage and restrained from axial movement, a reversible motor operatively connected to said screw, a nut threaded on the screw, said carriage having means cooperable with the nut to permit rotation thereof but restrain axial movement of the nut relative to the carriage, a fixed stop member extending in parallel spaced relation to the screw and being operable to restrain rotation of said nut upon rotation of the screw in both directions, and nut restraining members arranged at each end of 50 said fixed stop member, one of said restraining members being operable to restrain rotation of the nut in one direction and the other member to restrain rotation of the nut in the opposite direction.

55. Mechanism for actuating a reciprocating carriage comprising a frame, a carriage actuating screw journalled in the frame, a nut threaded on the screw and being operatively connected to said carriage and rotatable relatively thereto, a stop member extending in parallel spaced relation to the screw and cooperable to restrain rotation of said nut about the axis of the screw,

whereby upon rotation of said screw, said nut and carriage are moved axially of the screw, a latch member pivotally mounted at each end of said stop member and having a projection, said latch member being normally positioned with their respective projections forming a continuation of said fixed stop member and being movable about their pivots to permit rotation of said nut by the screw as the nut is advanced from the fixed stop member to said latch.

5. Actuating mechanism for a reciprocating carriage comprising a frame, a carriage actuating screw journaled on the frame, a nut threaded on said screw and being operatively connected to the carriage for rotation relative thereto, a 15 fixed stop member extending in parallel spaced relation to said screw and being cooperable with said nut to restrain rotation thereof upon rotation of said screw in both directions, a movable stop at each end of said fixed stop, one of said 20

movable stops being operable to restrain rotation of said nut upon rotation of the screw in one direction only, and the other movable stop being cooperable to restrain rotation of said nut in the opposite direction only.
